UNITED STATES PATENT OFFICE.

EDWARD A. GRAVES, OF JAMESTOWN, NEW YORK.

PANTS AND SHIRT GRIP.

1,321,735.

Specification of Letters Patent. Patented Nov. 11, 1919.

Application filed January 28, 1919. Serial No. 273,516.

To all whom it may concern:

Be it known that I, EDWARD A. GRAVES, a citizen of the United States, residing at Jamestown, in the county of Chautauqua 5 and State of New York, have invented certain new and useful Improvements in Pants and Shirt Grips, of which the following is a specification.

The present invention relates to garment 10 supporting means and more particularly to a clip for preventing the upward creeping of the shirt and the downward slipping of the trousers.

The invention obviates the use of suspender 15 and the necessity for providing buttons upon the waist band of pants since the clip is of such construction as to positively engage the waist band of trousers and the skirt portion of a shirt with the result that 20 the trousers are supported by the shirt and in turn prevent the upward creeping of the shirt by reason of the intermediate connection resulting from the use of the clip which engages both the shirt and the trousers.

25 The drawing illustrates a preferred embodiment of the invention. However, it is to be understood that in adapting the same to meet different conditions, various changes in the form, proportion, and minor details 30 of construction may be resorted to without departing from the nature of the invention as claimed hereinafter.

In the drawing hereto attached,

35 Figure 1 is a front view of a clip embodying the invention showing the same applied.

Fig. 2 is a view similar to Fig. 1 with the shirt omitted and illustrating the clip as seen from the inner side of the waist band.

40 Fig. 3 is a vertical section on the line 3—3 of Fig. 1.

Fig. 4 is a detail showing the clip as it appears when applied to the shirt.

Fig. 5 is a detail perspective view of the 45 clip.

Corresponding and like parts are referred to in the following description and indicated in the several views of the drawing by like reference characters.

The clip is of oblong form and is prefer- 50 ably constructed of a sheet metal blank and

comprises a body portion 1. One end of the clip has an opening therein of approximately key-hole shape, such opening comprising an enlarged portion 2 and a narrow portion 3. The opposite end of the clip is 55 bent upon itself to provide a hook, the bill portion 4 of which flares slightly to facilitate the engagement of the hook with the upper edge of the waist band of pants or trousers. The butt portion of the hook is 60 contracted, as indicated at 5 so as to bite the edge portion of the waist band and prevent possible displacement of the clip after the same has been properly engaged with 65 the waist band.

In practice the skirt portion of a shirt 6 is engaged with the lower end of the clip by gathering a portion of the shirt and passing it through the opening 2 and then drawing it into the narrow or contracted 70 portion 3 of the opening. The hooked end of the clip is now engaged over the waist band 7 of the trousers or pants and is drawn downward to cause the upper edge of the waist band to be firmly gripped between the 75 contracted portion 5 of the hook. It will be understood that the clip forms positive connecting means between the shirt and pants, thereby preventing the upward creeping of the shirt and the downward displacement 80 of the pants, hence the necessity for providing suspenders or attaching buttons to the waist band of pants or trousers is wholly obviated.

The foregoing description and the drawings have reference to what may be considered the preferred, or approved, form of my invention. It is to be understood that I may make such changes in construction and arrangement and combination of parts, materials, dimensions, et cetera, as may prove expedient and fall within the scope of the appended claim.

Having thus fully described my invention, what I claim as new and desire to secure by Letters Patent is:—

A pants and shirt grip, comprising an elongated body having a key-hole shaped opening at one end and a hook at its opposite end consisting of a portion of the 100

body folded upon itself, said hook embodying a butt, shank and bill and having its bill flared and both the bill and shank drawn in adjacent the butt to form pronounced gripping portions and a contracted opening to the butt.

In testimony whereof I affix my signature in presence of two witnesses.

EDWARD A. GRAVES.

Witnesses:

MARY M. WOODS,

LAWRENCE U. HALLECK.
